ROBERT CHRISTOPH FREDERIK VOGEL, OF HAMBURG, GERMANY, ASSIGNOR TO FIRM
OF VOGEL & HALKE, OF HAMBURG, GERMANY.

COIN-ACTUATED SCALE.

Application filed June 4, 1928, Serial No. 282,757, and in Germany September 21, 1926.

The present invention refers to a coin actuated scale, in which the movement of the hand lever is transmitted to a locking lever by a coin, token, counter, or the like in such manner that by the said lever an indicating mechanism is released to allow the same to adjust itself to indicate the weight. For transmitting the movement of the hand lever to the locking lever two slides are operated in the same direction preferably in a straight line, and by means of the coin inserted between them the movement of the one slide engaged by the hand lever is transmitted to the other slide, which may be termed the counter-slide, which effects the release of the locking lever. To ensure a correct operation of the scale and the proper sequence of the single functions the following provisions are made. The counter-slide does not effect the adjustment of the locking lever in the position of releasing the indicator until it returns after the hand lever is allowed to slip back; the return movement of the locking lever into locking position is slowed down by a damping device; the last part of the return movement of the counter-slide is retarded, so that the slide operated by the hand lever will be moved to its initial position sooner than the counter slide.

The releasing movement of the locking lever will not commence before the return movement of the counter slide to safeguard the scale against operating before both slides have completed their movement. Thereby any misusage of the scale is prevented. The slowing down of the return movement of the locking lever ensures the free play of the indicating device for a sufficient length of time to permit the handle of the indicator to be unobstructedly operated by the returning locking lever in proper manner. The retardation of the last part of the return movement of the counterslide thus producing a relative advance movement of the other slide has the effect of separating the slides so that the coin is no longer held between the two slides, being permitted to drop down.

Misusage of the scale therefore is prevented by the fact that the indicator does not start the very moment a pull on the hand lever is exerted, but when the hand lever is allowed to return and moreover by the fact

that up to this moment the coin is held between the two slides.

55

Figs. 1 and 2 show the indicator mechanism in plan in two different positions, the dial together with the pointer being removed.

Figs. 3 and 4 are detail views at right angle to one another of the slides holding a coin.

The shaft 1, on which the usual pointer (not shown) is attached, is rotated by a rack 2 engaging a toothed wheel 2' keyed to the shaft 1. The rack 2 is rotatably connected with the usual bell crank lever 3, which is connected with the draw bar 3' connected with and operated by the platform by the weighing spring 3'', as is well known in scales of this kind. As is also well known the draw bar is sectional, the lower section being connected to the main springs 3'', which are tensioned by the weight of the person standing on the platform, while the upper section of the draw bar, owing to its being held by the locked bell crank lever 3, will only follow the tension of the spring 3'' when the bell crank lever 3 is released to operate the indicator proportionately to the distance the two sections of the draw-bar are separated, which distance depends on the weight of the load on the platform of the scale. Moreover, as is also known, on the indicator shaft 1 a locking disk 4 is firmly mounted. Into the gap of this locking disk 4 a tooth 6 of a locking lever 5 engages in the zero-position of the pointer.

The hand lever 7 which projects out through a slot 7' of the casing A, is pivoted at 7'' and held in its initial position by a spring 7'', Fig. 1. A lateral arm 8'' of the hand lever has a slot 8' into which engages a stud 8 mounted on a slide 9. This slide 9 has a longitudinal slot 9'' into which engage fixed guide studs 10 in such manner that the slide 9 may reciprocate in longitudinal direction on the studs 10 when the hand lever 7 is operated.

In line with the slide 9 a counter slide 11 is guided by pin-and-slot-connection on a prismatic guide piece 12, a spring 13 being adapted to pull the counter slide 11 in the direction towards the slide 9. The end of this counter-slide 11 is bifurcated, the

100

95

105

prongs of which bifurcation being bridged by a rectangular head 14, Figs. 3 and 4. The guide piece 12 forms a stop for the counter slide 11 when subjected to a pulling 5 action by the spring 13 in such manner that the head 14 engages into a gap 14' in the wall of the coin chute 15. When the slide 9 is moved its preferably reduced end is adapted to freely enter the bifurcation of 10 the counter-slide 11.

When a coin is introduced into the coin slot it will run along the coin chute 15 up to the head 14 of the counter slide. When thereupon the hand lever 7 is pulled the 15 slide 9 will hit against the coin, and by the aid of this coin the counter-slide 11 will be moved, whereby the coin is removed from the gap 14' of the coin chute, but will be still held between the slide 9 and the counter-slide 11. The reciprocation of the two slides will thus also effect a free movement of the coin.

A pawl 16 is rotatably mounted on the counter-slide 11 and connected with one end 25 of the spring 13, by which it will be held in position engaging a stop 17 mounted on the counter-slide. When the counter-slide is longitudinally moved the pawl 16 will slip past a tooth 18 on the locking lever 5, Fig. 30 2. When, however, the hand lever 7 is allowed to slip back the coin will be released and may drop down to the bottom of the casing or through an opening in the bottom of the casing into a reservoir. To ensure 35 this operation the counter-slide 11 should not return together with the slide 9 immediately. This object in view a double-armed lever 19, 20 is pivotally connected with a stud 23, one arm 20 of said lever being bifurcated at the end to embrace the stud 8, while the arm 19 in the normal position of 40 the counter-slide, Fig. 1, projects into an opening 21' of the arm 21, mounted on the counter-slide 11. In the described movement 45 of the counter-slide 11 the hand lever 7 by the intermediary of a spring 24 will oscillate the double-armed lever 19, 20 in such manner that the arm 19 is drawn out of the opening 21' of the arm 21 and bears 50 with its end against a full part of the arm 21. When then the hand lever is released the arm 19 will prevent at first the return movement of the counter-slide 11, it being engaged by the arm 21, Fig. 2. Thus, not until 55 the hand lever has returned into its normal position, Fig. 1, it effects an oscillation of the lever 19, 20 by the stud 8 in such manner that the arm 19 will again enter the opening 21' of the arm 21.

60 On the return movement of the counter slide 11 its pawl 16 acting on the tooth 18 effects a slight oscillation of the locking lever 5 to allow the locking tooth 6 to be withdrawn from the locking disk 4, whereupon the indicator mechanism will be moved

into a position corresponding to the load of the platform of the scale the pointer thus indicating the weight.

To avoid the locking lever 5 being hindered in its movement, it is connected with 70 an air brake 22 adapted to retard its return movement.

To prevent the coin from dropping down into the reservoir in case the hand lever 7 is allowed to slip back before it has finished 75 its operation a device is arranged to obstruct the return movement of the hand lever into its initial position before it has been moved into its end position. This device comprises a short rack 25 firmly attached to the bottom of the casing, the serration of this rack being very fine and adapted to be engaged by a tooth 26 on a pawl rotatably connected to a stud 27 on the slide 9. This pawl is connected with 80 the spring 24 which thus influences the pawl. When the slide 9 is moved from its initial position to its end position without interruption and also when moved back again from the end position into the initial 85 position the tooth 26 will not engage the teeth of the rack 25 in either direction. If, however, the hand lever is allowed to slip off prematurely the tooth 26 will engage the return movement owing to the fact that the point of the tooth 26 has a distance from the centre line of the stud 27 slightly larger than the distance of the latter from the root of the teeth of the rack. 100

1 claim:—

1. A coin actuated scale of the type in which the operation of the hand lever on a locking mechanism for the indicating mechanism is transmitted by a slide operated by 105 said hand lever and by a counter-slide by the aid of a coin coupling the two slides together in one direction, comprising a damping device and a locking lever, the damping device adapted to slow down the movement 110 of a locking lever forming part of said locking mechanism on the return movement of the counter-slide when the hand lever is allowed to slip back for the object of releasing the indicating mechanism from its locking 115 position.

2. A coin actuated scale according to claim 1, comprising a member (such as a double-armed lever) adapted to initially retard the return movement of the counter-slide to release the coin by the fact that the said member is adapted to be moved into the path of and to engage the counter-slide on the hand lever being operated and to release the counter-slide on the hand lever returning into its initial position. 120

3. A coin actuated scale according to claim 1, comprising a locking lever and a locking disk on the dial shaft forming said locking mechanism, a pawl on the said 125

counter-slide and a tooth on the locking lever, the pawl being constructed to slip past said tooth on the counter-slide being operated by the hand lever by the intermediary of the first named slide and the tooth on the locking lever being positioned to be engaged by the said pawl on the counter-

slide returning to its initial position to release the locking lever from engagement with the locking disk.

10

In testimony whereof I have signed my name to this specification.

ROBERT CHRISTOPH FREDERIK VOGEL.
